UNITED STATES PATENT OFFICE.

EARL E. GARRISON AND WAYNE GARRISON, OF ALBANY, NEW YORK, ASSIGNEES TO
MAYER & GARRISON, OF ALBANY, NEW YORK, A FIRM COMPOSED OF EARL GAR-
RISON, WAYNE GARRISON, AND SAMUEL M. MAYER.

TORCH.

Application filed July 15, 1921. Serial No. 434,929.

To all whom it may concern:

Be it known that we, EARL E. GARRISON and WAYNE GARRISON, citizens of the United States, and residents of Albany, in the 5 county of Albany and State of New York, have invented certain new and useful Improvements in Torches, of which the following is a specification.

The present invention relates to improvements in torches, and the objects and advantages thereof are to simplify in general the character and constructions of blow torches, to reduce the expensive manufacture and the amount of material required to produce the same, to dispense with the necessity for providing a hand pump in conjunction with the torch, to make the feeding of the fuel to the burner automatic, and to pre-heat and vaporize the fuel prior to its issuance 20 through the discharge aperture where it ignites and is burned completely and without any appreciable formation of residue deposits.

As constructed at the present time blow 25 torches are provided with liquid fuel reservoirs at the sides of which are carried reciprocating pumps which must be actuated by hand several times preliminary to the lighting of the torch in order to place the liquid fuel body under that pressure necessary to raise it to the nozzle or burner orifice.

With this in view, it is the object of the present invention to provide a commercial blow torch composed of only two parts, the 30 fuel reservoir or receptacle and a piping or tubing connected thereto and provided with a discharge orifice placed relatively in a helix or convoluted portion of the piping or tubing to the end that the heat from the 35 flame will envelop parts of the helix or turns of the convoluted portion and vaporize the fuel which is received from the tubing or piping and place it initially in a condition for combustion, and in employing capillary 40 wicks or other devices embodying the principle of capillary attraction to raise the liquid fuel from the receptacle to the helix or convoluted portion of the tubing or piping without any interruption in this capillary 45 means and without allowing the capillary means to enter the helix or coil which thus provides a retort of a relatively great capacity for maintaining a comparatively large

volume of the fuel in a vaporized state in readiness for combustion.

The area of the vapor space within the helix or coil and the diameter of this helix or coil is so proportioned relatively to the discharge orifice that a back pressure will be created such as will permit the gas to 55 back up into the upper portion of the receptacle and form a pressure head therein which will assist the action of the capillary wicks and at the same time will not interfere with the free flow of the liquid fuel through the 60 65 capillary passages throughout the wicks.

With the foregoing and other objects in view, the invention will be more fully described hereinafter, and will be more particularly pointed out in the claims appended 70 hereto.

In the drawing, wherein like symbols refer to like or corresponding parts throughout the several views,

Fig. 1 is a perspective view of an improved 75 automatic self-blowing torch constructed according to the present invention; and

Fig. 2 is a vertical sectional view taken through the same with a portion of the helix or coil in elevation.

Referring more particularly to the drawing, 1 designates the top, 2 the cylindrical side wall, and 3 the bottom of a comparatively shallow, squat and flat receptacle or reservoir adapted to contain a liquid fuel 80 such as gasoline or the like which may be introduced through an opening in the bottom normally held closed by a screw or other plug 5 and having a thumb piece or operating part 6 by which it may be turned 85 into and removed from the opening. Preferably this plug 5 and its operating part 6 are disposed within a cavity 7 in the bottom 3 which may be conveniently constructed by pushing in the material of the bottom during 90 its manufacture. The idea is to have the plug and its operating part set within the bottom so as not to interfere with the flat bottom surface 3 or the resting of the torch on a flat supporting surface. The plug 5 95 is made both liquid and gas tight so as to avoid the loss of any liquid and to retain the gas pressure within the receptacle.

In the top 1 of the receptacle openings 8 and 9 are made preferably to opposite sides 100 of the center of the receptacle and through

these openings are placed the lower ends of tubular legs 10 and 11 which are formed from the end portions of a single piece of piping or tubing. The legs 10 and 11 are 5 slightly bowed for example as shown, although they may be made straight if desired, and a preferred manner is to have these legs extending directly and vertically upward from the receptacle so that in addition to 10 forming channels for the passage of the liquid fuel upwardly to the burner orifice, they moreover, when the torch is cold, afford a handle by which the device may be lifted about and transported.

15 At the intermediate portion of the tubing or piping which is that disposed uppermost a helix or coil is made consisting of overlapping upper turns 12 and 13 which lie horizontally side by side and merge at their 20 opposite ends into the upper parts of the legs 10 and 11, and a single lower partial convolution 14 which at its opposite ends extends into the upper turns 12 and 13 and is of course wound in the same movement 25 therewith.

A discharge orifice 15 is produced at the inner side of the part convolution 14 at substantially the central and lowermost portion thereof in position to direct the issuing 30 gases and the ignited flame directly upward in fan shape beneath and through the turns 12 and 13 so that the latter turns form in effect an overlying retort containing the liquid gasoline which is vaporized by the 35 heat of the flame preliminarily to its arrival at the discharge orifice 15. The diameter of this orifice 15 is made comparatively 40 small as compared with the diameter of the partial convolution 14 and the turns 12 and 13 and of course the length of these turns and partial convolutions are such as to form 45 a chamber of considerable capacity for holding a large supply of vaporized fuel or gas which accumulates under pressure and issues with great force through the discharge 50 orifice 15 thereby placing the fuel under most beneficial conditions for its complete and ready combustion and for the spreading and distribution of the flame in a wide- 55 spread or fan-like form to envelop all parts of the turns 12 and 13 of the helix.

The decreased diameter of the discharge 60 orifice 15 restricts the flow of the vaporized fuel, and as a consequence sets up a back pressure in the retort or turns 12 and 13 and causes the accumulated gas or a portion of it to descend through the legs 10 and 11 into the upper portion of the receptacle 2 where it collects and forms a head of a pressure 65 which varies from time to time and which acts upon the upper surface of the liquid 4 tending to drive it upwardly through the capillary spaces and channels provided by a pair of wicks 16 and 17 having their lower 70 ends disposed in the body of the liquid 4 and extending upwardly through the legs 10 and 11.

and extending upwardly through the legs 10 and 11.

The upper ends 18 and 19 of the capillary wicks 16 and 17 are shown in Fig. 2 to extend up to the initial and terminal points 70 of the helix but not to enter such helix, and this construction is found satisfactory for the reason that it removes the fabric structure of the wicks from the disintegrating influence of the heat developed upon the 75 helix by the flame used to vaporize the fuel and moreover the termination of the upper ends of the wicks outside of the helix leaves the latter entirely free on its interior thereby increasing its capacity and affording a 80 relatively large space for the back pressure of the gas to collect and otherwise not interfering with the free and ready vaporization of the fuel.

In the use of a device of this character, 85 fuel from the liquid body 4 within the flat receptacle is at all times raised, by virtue of the capillary attraction through the wicks 16 and 17, to the initial and terminal points of the helix, so that by the application 90 of an ignited match within the helix the fuel will rise from the ends 18 and 19 of the wick under the vaporizing influence of the heat practically instantaneously and, finding its way to the orifice 15, will be discharged and ignited by the match all in one 95 operation, without having to resort to any initial pumping or any extraneous operation that would involve a complicated structure of torch or the necessity for preliminary 100 action of any kind.

After the burner has been started as just described, the action will be a continuous one from then on inasmuch as the fuel consumed will create a draft through the capillary passages of the wicks 16 and 17 and will create voids to be filled by continuous capillary action which will go on automatically and keep maintaining a full and necessary supply of the fuel to the heated helix 110 and the burner orifice.

At the same time the accumulated vapor within the helix will not escape through the restricted orifice 15 as rapidly as it is vaporized and some back pressure of the gas will 115 be created. This accumulation of gas will tend to drive a portion of the vapor down through the legs 10 and 11 and into the upper portion of the receptacle forming a head there acting on the surface of the liquid and tending to drive it upwardly through the legs and through the capillary passages of the wicks. This descent of the gas through the legs 10 and 11 will not be interfered with by the wicks 16 and 17 inasmuch as there are 120 many interstices and channels through the openwork structure of the wicks through which gases may readily find their way.

We have illustrated and described a preferred and satisfactory embodiment of our 130

invention, but it is obvious that changes may be made therein within the spirit and scope thereof, as defined in the appended claims.

What is claimed is:

- 5 1. A torch comprising a receptacle forming a base, for the torch and being hollow to receive liquid fuel, said receptacle being substantially flat and provided with a normally closed filling opening made gas and liquid tight, a piping having its ends inserted through the top of the receptacle and in communication with the interior thereof, said ends of the piping being secured in gas tight fashion in the receptacle top, the pipe 10 being provided at its intermediate portion above the receptacle with convolutions having at the base of the same an orifice for the escape of the gas and acting to direct the gas and the flame formed by the combustion 15 of the same upwardly through the convolutions whereby to vaporize and gasify the liquid fuel in the convolutions flowing from the receptacle to the orifice, and capillary means in said pipe having the lower ends 20 thereof disposed in the liquid fuel in the receptacle, said capillary means extending continuously up to but not entering the convolutions of the piping, said convolutions of the piping being left free and unimpeded.
- 25 2. A self-blowing torch comprising a fuel receptacle and a pipe carried thereby, said pipe being coiled intermediate its ends and having its ends secured through the top of said receptacle with the convolutions of the pipe spaced above the receptacle, and separate wicks arranged in the ends of the pipe and extending at their lower ends into said fuel receptacle and extending at their upper ends to points adjacent to the coiled portion 30 of the pipe whereby to feed fuel from the receptacle up into the pipe, the coiled portion of the pipe having an opening at its lower side through which vapor generated in the coiled portion of the pipe is adapted to partially escape for burning within the coiled portion of the pipe, the burning of said gas being adapted to heat the coiled portion of the pipe and generate gas therein whereby 35 said gas is adapted to exert a backward pressure through the ends of said pipe into the receptacle for forcing the feeding of the fuel upwardly into the pipe, and means for venting the receptacle whereby to relieve the pressure on the fuel therein.
3. An automatic torch comprising a substantially thin flat receptacle forming a low base and being closed on its top and sides and provided with a bottom having a filling opening therein, means to close the filling opening and to seal the same both air and gas tight, a single length of tubing bent at its end portions to provide a pair of spaced apart legs extending substantially vertically above the receptacle and having the lower ends of the legs pushed through the top of the receptacle and secured tightly therein, a helix formed of the intermediate portion of the tubing between the top parts of the legs and forming a continuation of the same, said helix at its base and on its interior side being provided with an orifice of smaller port area as compared with the diameter of the helix whereby to set up a back pressure of the gases generated in the upper portion of the helix, and two independent capillary wicks having their lower portions extending down into the receptacle and lying within the legs but having their upper ends terminating outside of the helix and being continuous from the helix down to the interior of the receptacle.
4. A torch comprising a receptacle being hollow to receive liquid fuel and provided with a normally closed filling opening, a piping having its ends inserted through the receptacle and in communication with the interior thereof, said ends of the piping being secured to the receptacle in gas tight fashion, the piping being provided at its intermediate portion and at a higher elevation than the receptacle with convolutions having an orifice at one side for the escape of the gas and acting to direct the gas and the flame formed by the combustion of the same against the opposite side of the convolutions whereby to vaporize and gasify the liquid fuel in the convolutions flowing from the receptacle to the orifice, and capillary means in said pipe having the lower portion thereof disposed in the liquid fuel in the receptacle and adapted to raise the fuel to the convolutions.

In testimony that we claim the foregoing as our invention, we have signed our names hereunder.

EARL E. GARRISON.
WAYNE GARRISON.
